ATTORNEY

UNITED STATES PATENT OFFICE.

LEO J. SCHUMACKER, OF DAYTON, OHIO.

CURLING-IRON HOLDER.

Application filed February 4, 1924. Serial No. 690,399.

To all whom it may concern:

Be it known that I, LEO J. SCHUMACKER, a citizen of the United States, residing at Dayton, in the county of Montgomery and 5 State of Ohio, have invented certain new and useful Improvements in Curling-Iron Holders, of which the following is a specification.

This invention relates to new and useful 10 improvements in curling-iron holders.

It is the principal object of the invention to provide a simple and efficient medium 15 for holding curling-irons or like instruments in a vertical or a horizontal position. The iron or other instrument may not only be firmly and conveniently supported by the holder in a horizontal position upon a table, but its position may be easily reversed in 20 the holder for support in a vertical position from a projection on a wall.

In the accompanying drawings, Figure 1 is a perspective view of my improved curling-iron holder. Figure 2 is a top plan view thereof. Figure 3 is a longitudinal, 25 sectional view taken through the same. Figure 4 is an end view of the lower part of the holder. Figure 5 is a view of its upper end. Figure 6 is a side elevational view of the holder when supporting an electric 30 curling-iron in a vertical position. And Figure 7 is a side elevational view of it when supporting an electric curling-iron in a horizontal position.

Referring to the accompanying drawings, 35 for a detailed description of my invention, the numeral 1 designates a base that is preferably constructed in elongated, hexagonal form from wood. Secured by screws 2, 2 or other suitable fastening elements to the 40 middle part of the base 1, is a metal supporting member 3 having up-turned ends 4 and 5. The contour of the bottom of the supporting member 3 preferably conforms to that of the base 1, although its shape, as 45 well as the shape of the base itself, may be varied if desired.

The up-turned end 4 of the supporting member 3 terminates in a wide bifurcated portion with a circular aperture 6 or any 50 other form of prong-receiving recess below

it. The other up-turned end 5 of the supporting member terminates in a bifurcated portion which is longer and narrower than that of the up-turned end 4.

In Figures 6 and 7 the numeral 7 designates an electric curling-iron of a standard type. When it is desired to support this curling-iron, or any other like instrument, in a horizontal position upon a table 8, for instance, the handle part of the iron is placed on the bifurcated portion of the up-turned end 4 of the supporting member 3 as shown in Figure 7, with the front end of the iron resting in the bifurcated portion of the up-turned end 5 of said supporting member. The iron will thus be firmly held by the supporting member in a position that is convenient for removal and one in which it will not contact with the table.

When it is desired to suspend the curling-iron from a wall or other structure, its position in the holder is reversed so that the front part of it may project through the aperture 6, with its rear end firmly 75 lodged in the bifurcated portion of the up-turned end 5 of the supporting member as shown in Figure 6. An electric cord 8^a connected to the handle part of the iron, may then be wrapped around it as desired.

Secured to the upper end of the base 1 is a screw-eye 9 for connection to a hook 10 secured to a wall 11, so that the holder and the curling-iron which it supports, may be suspended therefrom. The hole 6 in the up-turned end 4 of the supporting member 3, receives the front part of the curling-iron when in a vertical position, so that it may be firmly held without being permitted to dangle. When it is desired to remove the iron from the holder, it is only necessary to lift it far enough to clear the aperture 6, whereupon the base 1 may be taken off the hook 10 and placed upon the table 8. The iron may then be placed in a reverse position upon the up-turned ends of the supporting member 3 for support in a horizontal position until used.

Having described my invention, I claim: A holder for supporting a curling-iron 100

2
in a horizontal or a vertical position, comprising a base, a supporting member secured thereto having up-turned ends to hold said iron in a horizontal position, one of said ends being bifurcated and the other end having an aperture to receive, and prevent from dangling, the front part of the curling-iron when its handle part is supported

in a vertical position by the bifurcated end of the supporting member.

10
In testimony whereof I have hereunto set my hand this 2d day of February, 1924.

LEO J. SCHUMACKER.

Witness:

HOWARD S. SMITH.
